F. Thurston Haugh & Co.

ATTY'S

UNITED STATES PATENT OFFICE.

HENRY T. KRUSE, OF GULL LAKE, SASKATCHEWAN, CANADA.

RAIL.

1,355,400.

Specification of Letters Patent. Patented Oct. 12, 1920.

Application filed February 3, 1920. Serial No. 356,010.

To all whom it may concern:

Be it known that I, HENRY T. KRUSE, a subject of the King of Great Britain, a resident of the town of Gull Lake, Province of 5 Saskatchewan, Dominion of Canada, have invented certain new and useful Improvements in Rails, of which the following is a specification.

This invention relates to improvements in 10 rails and means for securing the same in position, and the objects of the invention are to facilitate assembling the rail and positioning it on a tie, to prevent lateral displacement of the rail when so positioned, 15 to provide means whereby a tie will be properly engaged with the road bed without liability of displacement due to vibration or other causes, and generally to adapt the several parts to better perform the functions 20 required of them.

Other objects will be made clear as the specification develops.

So that the nature of my invention may 25 be better understood reference is made to the accompanying drawings in which an embodiment of the invention is illustrated.

In the drawings:

Figure 1 is a fragmentary perspective 30 view of a tie showing the improved rail mounted thereon.

Fig. 2 is a transverse section through the rail and tie.

Fig. 3 is a plan view of the tie.

Fig. 4 is a perspective view looking from 35 the underside of the means for locking the rail against lateral displacement.

Fig. 5 is a fragmentary perspective view of a rail.

Fig. 6 is a perspective view of one of the 40 side members of the rail.

Fig. 7 is a perspective view of the means for securing one of the locking members shown in Fig. 4 in engagement with the tie.

Fig. 8 is a vertical section of the same.

45 Fig. 9 is a plan view of the securing means shown in Fig. 7.

Like characters of reference refer to like parts in the several figures.

Referring to the drawings; A represents 50 the improved rail and B the improved tie, the rail comprising a member 10 consisting of a ball head and the integral web 11, which has an orifice 12 therethrough.

The rail 10 is held between a pair of angle 55 members 13 each provided at the lower end with a projecting flange 14 which holds the

vertical arms of the angles in spaced relation to accommodate the web 11 and the said vertical arms are provided with orifices 15 designed to be arranged in alinement with 60 the orifice 12.

The rail A comprising the member 10 and the angle members 13 is held in position by a pair of clamping members 16 and 17 located on opposite sides of the rail and 65 provided with pin projections 8 and 9 which engage with the orifices 15 and 12.

The clamping member 17 is provided with an angle shaped locking member 18 on the lower face and a pin locking member 20 70 provided with an enlarged head 21.

The tie B is provided with a plurality of keyhole slots 22 and 23 and a slot 24 arranged in alinement with keyhole slots 23 and 22 and the angle shaped locking member 75 18 on the clamping member 17 engages the slot 24 and the pin locking member 20 engages one of the keyhole slots 23.

It will be clear that on longitudinal movement of the member 17 the locking member 80 18 and the enlarged head 21 of the pin locking member 20 engage with the underface of the top of the tie B.

The clamping member 16 is provided with a pin locking member 25 provided with an 85 enlarged head 26, and the outer end of the clamping member is provided with a recess 27.

The pin locking member 25 engages with one of the keyhole slots 22 and on longitudinal 90 movement of the clamp 16 the enlarged head 26 of the said locking member engages with the under face of the top of the tie B.

A locking member C is formed with a center cylindrical body portion 29 having an 95 eccentric cylindrical flange 30 on the lower end, and a rectangular flange 31 on the upper end, the cylindrical flange 30 being provided with a projecting tongue 32, and this eccentric flange 30 and tongue 32 engage 100 with the outer keyhole slot 22 when the clamp 16 has been positioned.

After the flange 30 and the tongue 32 pass through the slot 22 the locking member is rotated so that the tongue 32 underlies the 105 lower face of the tie B, and the upper flange 31 engages with the outer end of the clamping member 16, so securing the locking and the clamping member in position.

A key 28 passes through the locking member and is arranged to prevent the said member being rotated to unlock the same. The 110

key 28 and head of the locking member are inclosed by a cap 34.

The tie is formed with an upper portion of inverted channel formation having its 5 lateral walls diverging as shown at 35, the walls terminating in outturned flanges 36.

The tie B is closed by a bottom member 37 having its longitudinal edges 38 formed with inclined U-shaped edges which engage 10 the flanges 36 and complete the box construction of the tie.

The bottom member 37 becomes embedded in the railroad bed and is prevented from moving off the U-shaped inclined edges, so 15 that the tie is properly anchored in place.

The rail and the tie can be readily assembled and are not liable to get out of repair.

As many changes could be made in the 20 above construction and many widely different embodiments of my invention within the scope of the claims, constructed without departing from the spirit or scope thereof, it is intended that all matter contained in 25 the accompanying specification and drawings shall be interpreted as illustrative and not in a limiting sense.

What I claim as my invention is:

1. A device of the class described comprising a ball head having a depending web, 30 a pair of angle members having projecting portions at the lower end designed to abut to space the angle members to accommodate the depending web, a pair of clamping members, a box tie, and means whereby the 35 clamping members will make sliding engagement and be locked to the tie to hold the angle members and rail in position.

2. A device of the class described comprising a rail member, angle members 40 embracing the rail, a box tie, clamping members adjustably mounted on the box tie and designed to secure the rail and angle members in position, and locking members having eccentrically arranged flanges and key 45 means for holding the clamping members in locked position.

In witness whereof I have hereunto set my hand in the presence of two witnesses.

HENRY T. KRUSE.

Witnesses:

LOUIS ADOLPH,
R. E. ALEXANDER.
